UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,293,888.

Specification of Letters Patent. Patented Feb. 11, 1919.

Application filed July 31, 1916. Serial No. 112,244.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

One of the objects of my invention is to provide a means in a double ended friction gear in which the recoil of one set of compression resisting elements will be independent of the other set of compression resisting elements. Other objects will appear from the description of my invention herein following.

In the drawings forming a part of this specification, Figure 1 is a horizontal section, partly in top plan, of a draft rigging embodying my invention. Fig. 2 is a cross section taken on line 2—2 of Fig. 1. Fig. 3 is an enlarged detail showing in vertical longitudinal section the elements of my retaining bolt coupling feature. Fig. 4 is a perspective view of one portion of a coupling member, and Fig. 5 is a perspective view of the other portion of the coupling member.

Referring to the drawings, the numeral 6 indicates draft members, or that part of the car underframe to which the draft rigging is applied, 7—7 the front stop members and 8—8 rear stop members, all of usual construction. The draft gear, indicated at 9, is mounted between the draft members and is supported in its position by the tie plate 10, which is suitably secured to the draft members, as for instance by the bolts 11—11.

The draft gear is of the double-ended type and comprises a hollow shell, preferably of cylindrical form, 12, open at either end, as clearly shown in Fig. 1 of the drawings, and provided intermediate its ends with a transverse diaphragm 13. The said diaphragm is centrally provided with a perforation 14, within which the retaining bolt coupling member 15, hereinafter more particularly described, is mounted. A chamber 16 is thus formed within the shell on either

side of said diaphragm, and each of said chambers contains a set of friction and spring elements, constituting a single compression resisting unit.

The elements in each of said chambers are substantially the same and it is only necessary to describe one of them. The said elements consist of the friction shoes 18—18, preferably three in number, the said friction shoes being provided with a spreading member, or wedge 19, the said wedge being adapted to be engaged by the adjacent follower 20 and seated between the said friction elements and the diaphragm of the shell are spring members, preferably comprising an outer spring 21 and an inner spring 22. At its inner end the outer spring is seated against the said diaphragm, and both of said springs at their outer ends are seated against the follower member 23, which engages the outer ends of the friction shoes. The inner ends of the spring coils are seated against the retaining bolt coupling member 15. A retaining bolt 25 is mounted in each chamber, being provided at its outer end with a nut 26 countersunk in the wedge, as at 27, and at its inner end with a head 28. The retaining bolt coupling member 15 is formed in two sections, one of said sections being represented in Fig. 4 of the drawings and the other in Fig. 5. The said sections are adapted to receive each a head of a retaining bolt and are provided with means, hereinafter more particularly described, to prevent the rotation of the bolt heads therein. One of the members, as for instance that indicated in Fig. 4, is provided with a shoulder 29, adapted to engage against the diaphragm 13. It is also provided with a projecting portion 30 which extends through the opening 14 in the said diaphragm. The said projection is provided with an internal face of substantially the same contour as that of the bolt head, in order to prevent the rotation of the retaining bolt head therein. This portion of the retaining bolt coupling member is provided with a longitudinal perforation 31 for the passage of the shank of the bolt. The other portion of the retaining bolt coupling member, as for instance that illustrated in Fig. 5, is provided with a body portion 32, having the longitudinal perforation 33 for the passage of the shank of a retaining bolt, and is adapted, through the shoulder 34 pro-

vided thereon, to interlock with the projecting portion 30 of the opposed part of the retaining bolt coupling member. The projecting member 30 is of sufficient length 5 to permit the reception therein of the head of the bolt passing through the opposed portion of the coupling member so that the opposed heads of both retaining bolts are, upon the assembling of the parts of the retaining bolt coupling member, within the groove which is shown in the projecting portion 30 illustrated in Fig. 4 of the drawing.

The position of the bolt heads within the retaining bolt coupling member is clearly illustrated in the enlarged detail shown in Fig. 3 of the drawings.

The projecting portion 30 is provided with a shoulder 35, back of which the shoulder 34 is adapted to engage, the said engagement being effected upon the assembling of the parts by sliding the portion of the retaining bolt coupling member, shown in Fig. 5 of the drawings, laterally into engagement with the portion thereof illustrated in Fig. 4 to their central position in reference to the shell.

It will be understood that the draft rigging is provided with a draw bar 36, the rear portion thereof being shown in Fig. 1 of the drawing, to which a yoke 37 is connected to effect a connection between the draft gear and the draw bar in a manner which is well understood.

In assembling the parts of the friction mechanism within the shell, one section of the retaining bolt coupling member, for instance that illustrated in Fig. 5, is mounted upon one of the retaining bolts, as for instance the front retaining bolt, shown in Fig. 1 of the drawings. Likewise, the other portion of the retaining bolt coupling member, as for instance that illustrated in Fig. 4, is mounted upon the other connecting bolt, as for instance the rear connecting bolt shown in Fig. 1 of the drawings. A retaining bolt is then inserted in each chamber of the cylinder, the portion of the coupling member 15, illustrated in Fig. 4 of the drawings, being passed through the opening 14 in the diaphragm 13, and the other portion of the retaining bolt coupling member is then brought into engagement at one side of the center and slipped laterally into position, until both connecting bolts are in their position along the axis of the shell and thereupon the springs and friction elements are inserted, the nuts upon the retaining bolts placed in position, and the parts of the draft gear are thus wholly assembled.

Heretofore, in double ended friction gears, where the same are provided with a single connecting bolt extending from one set of friction elements at one end, to another set 65 of friction elements at the other end, or

where the elements in one end of a draft gear casing are of different compression resisting capacity than those in the other end of the casing, great difficulties have been experienced in properly limiting the outward movement of the friction parts upon the recoil of the same, following a compression of the gear. For instance, where a single connecting bolt is used, under the circumstances set forth, the parts of greater compression 75 resisting capacity will be tardy in their release, compared to the parts having a lower coefficient of friction in the other end of the shell, and the parts because of this equality of action, when they finally come to rest, will 80 be found extended beyond the normal position which they are designed to take in the particular gear, while the parts that release tardily will be less extended than in the normal position for which they were designed 85 in the gear.

My invention, by reason of the means provided for holding the retaining bolt through the medium of the coupling member 15, overcomes this difficulty. That is, upon release 90 of the compression resisting parts, the shell will be in its central position in reference to the other parts of the draft rigging with which it is associated. It will be observed that upon the assembling of the parts, the inner coils being seated at their outer ends against the friction elements, and at their inner ends against the retaining bolt coupling member, will hold the parts of said coupling member in their fixed position and 100 will prevent any accidental displacement thereof.

I claim:

1. In a frictional shock absorbing mechanism, the combination with a double ended friction shell, of friction elements coöperable with said shell at each end thereof, spring means associated with each set of friction elements, and means, including a longitudinally extending bolt, associated with each 110 set of friction elements to limit the outward movement thereof with respect to the friction shell, said means at one end of the shell acting independently of the means at the opposite end of the shell.

2. In a shock absorbing mechanism, the combination with a shell, of separate compression-resisting members at either end of the shell, a retaining bolt for each set of compression-resisting members, and a coupling member for connecting said bolts.

3. In a shock absorbing mechanism, the combination with a shell, of separate compression-resisting members at either end of the shell, a retaining bolt for each set of compression-resisting members, and a coupling member connecting said bolts, said coupling member being secured to the shell.

4. In a shock absorbing mechanism, a shell provided with a plurality of chambers, a set 115

of compression-resisting elements in each of said chambers, a retaining bolt for each of said sets, and a coupling member for said bolts, said coupling member being secured to the shell.

5. In a shock absorbing mechanism, a shell, a diaphragm forming chambers in said shell, a set of compression resisting elements in each of said chambers, a retaining bolt for each of said sets, and a coupling member holding said retaining bolts end to end, the said coupling member being secured to said diaphragm.

6. In a shock absorbing mechanism, a shell, a member forming chambers in said shell, a set of compression resisting elements in each of said chambers, a retaining bolt for each of said sets and a coupling member for each of said retaining bolts, the said coupling members having interlocking portions.

7. In a shock absorbing mechanism, a shell, a member forming chambers in said shell, a set of compression resisting elements in each of said chambers, a retaining bolt for each of said sets and a coupling member for each of said retaining bolts, the said coupling members having interlocking portions, said coupling member being secured to the said chamber forming member.

8. In a shock absorbing mechanism, a shell, a diaphragm intermediate the ends of said shell, friction members and springs on either side of said diaphragm, a retaining bolt associated with each set of friction members and springs, and a coupling member for the said retaining bolt, the said coupling member extending through said diaphragm and being secured thereto.

9. In a shock absorbing mechanism, a shell, a plurality of sets of compression resisting members within said shell, a retaining bolt for each of said sets and a coupling member connecting said retaining bolts together, said coupling member comprising a plurality of parts, the said parts having interengaging flanges to connect them together.

10. In a shock absorbing mechanism, a shell, a diaphragm intermediate the ends of said shell, friction elements and springs

on either side of said diaphragm, a connecting bolt associated with each set of friction elements, coupling means for securing said bolts to the shell, said coupling means interlocking with the said diaphragm.

11. In a shock absorbing mechanism, a shell, a set of friction elements and springs in either end of said shell, a diaphragm in said shell separating said sets, and a connecting bolt for each of said sets secured to said diaphragm to limit the movement of the friction elements of each set away from the diaphragm.

12. In a shock absorbing mechanism, a shell, a chamber in either end of said shell, each chamber being provided at its inner portion with spring members and at its outer portion with friction elements, pressed against by said spring members, and a connecting bolt for each set of friction elements, the said retaining bolts being at their inner ends secured to the shell.

13. In a shock absorbing mechanism, a shell, a chamber in either end thereof, a diaphragm separating said chamber, springs mounted on either side of said diaphragm, a set of friction elements in each of said chambers and associated with the springs therein, a retaining bolt for each set of friction elements, and a coupling member for said retaining bolt, the said coupling member being secured to the said diaphragm.

14. In a shock absorbing mechanism, a shell, chambers in either end of said shell, a diaphragm separating said chambers, friction elements in each of said chambers, a retaining bolt for each set of friction elements, an interlocking coupling member securing the inner ends of said bolts in the diaphragm, and a spring mounted between each set of friction elements and the coupling member to hold the coupling member in locked position.

In witness that I claim the foregoing I have hereunto subscribed my name this 28th day of July, 1916.

JOHN F. O'CONNOR.
